GEORGE ADOLPH STEINER, OF SALT LAKE CITY, UTAH, ASSIGNOR TO STEINER SALES COMPANY, OF SALT LAKE CITY, UTAH, A CORPORATION OF UTAH

TOWEL CABINET

Application filed January 28, 1927. Serial No. 164,276.

My invention relates to the wall type of cabinet or one that is secured to a vertical wall or upright support in distinction from a cabinet that stands upon the floor although 5 the invention with suitable modifications may be embodied in the floor type of cabinet if desired.

The object of my present invention is to provide means whereby the support of the 10 clean towel roll and the feed rolls may be drawn forward to a point partially outside of the enclosing cabinet to the end that the attendant may with greater ease and facility load or fill the cabinet, preparing it for delivery 15 of the clean towel web.

A further object is to provide a cabinet of simple and inexpensive construction and one which will be simple of operation and strong and durable.

20 In the accompanying drawings forming a part of this specification,

Figure 1 is a vertical sectional view through a towel cabinet embodying my invention showing the parts in a position for delivery 25 of the clean towel;

Figure 2 is a similar view showing the position assumed by the towel cabinet apparatus when the attendant is in the act of loading or filling the cabinet; and

30 Figure 3 is a sectional view on the line 3—3 of Figure 1.

In the drawings, 2 represents the side walls of the cabinet; 3, the top thereof; 4, a hinged door which normally closes the open front 35 of the cabinet, and 5 is a bottom plate between which and the supporting wall of the cabinet a gap or opening 6 is provided for convenience in stretching the web of clean towel upwardly to the soiled towel take up roll.

40 Within this cabinet a frame composed preferably of metallic side plates 7 is provided with a connecting brace element 8, also preferably of metal, this bracing plate having a curved portion extending between and separating 45 the feed rolls and a downwardly and forwardly curved portion which forms a support for the clean towel 9. The frame is open at the front as indicated in the drawings so that when the door is open the attendant

50 may easily and quickly insert the roll of clean

towel into the cabinet. This roll is free to move back and forth on the supporting plate 8 to facilitate the unwinding of the towel web and the front of the plate has an upwardly projecting ledge or flange 10 with which the 55 towel roll will contact to limit its forward movement. The plate 8 in the normal position of the frame is adjacent the bottom 5 of the cabinet, the rear portion of the plate 8 forming a curved guide on which the web 60 of soiled towel may slide as the cabinet is used. The upper rear portions of the plates 7 have ears 11 thereon and comparatively long links 12 connect these ears with pivot pins 13 which are mounted in the upper rear 65 portions of the side walls of the cabinet.

These links in the normal position of the cabinet depend vertically at the rear thereof but when the front door is opened and the frame pulled outwardly the links 12 will 70 swing freely on their pivots and permit the frame to be drawn forward to a point partially outside the cabinet where the attendant can easily reach the mechanism to conveniently stretch the clean web to its usable position. The side plates 7 of the inner frame 75

have bearings for the take up feed rolls 14 and 15. These rolls are preferably of the same diameter and have peripheral surfaces adapted to adhere to the towel web and preferably this clinging effect is obtained by sanding the surfaces of these rolls or by the use of a rubber surface of suitable form so that when one roll is driven through the clinging

80 of the towel web thereto the other roll will 85 be operated also through the driving connection 16 between them. The curved plate 8 as described extends between these feed rolls so that there will be no danger of contact of their surfaces and contamination of 90 the clean towel web. The plates 7 have diagonal slots 17 therein adapted to receive shaft of a pinch roll 18 which roll, when the shaft is placed in the slots, will slide down by gravity or other means therein to a point near 95 the delivery feed roll 14 and when the web of clean towel is stretched upwardly from the roll over and around the pinch roll, the weight of the pinch roll will press this web against the roll 14 so that when the user pulls 100

on the web, power will be transmitted to the feed roll 14 to revolve it and in turn revolve the roll 15 operatively connected therewith. The side plates also have notches 17^a therein to receive the shaft of the pinch roll 18 during the operation of threading or stretching the towel web to the soiled towel roll or while the attendant is in the act of filling the cabinet. A stop device 19 is provided for controlling the operation of the delivery roll. This, however, I make no claim to in this application. When the web of clean towel is stretched over the pinch roll it is carried downwardly through a gap 20 between the plate 5 and the door of the cabinet and thence depends in a loose loop under the cabinet, the end of the web being carried upwardly and wrapped around a take up roll 21 that is mounted in guides 22 in the side walls of the 20 towel cabinet. These guides have notches 23 adapted to receive the shaft of the take up roll 21 when it is not in use. A suitable tension roll 26 is provided in the rear of the frame operating to make a slight bend in the 25 towel web and press it against the plate 8 and also has the function of smoothing out wrinkles or folds that may be in the towel web preparatory to its delivery to the take up roll. The position of the guides 22 in the 30 side walls of the cabinet is such that the take up roll 21 will be close to the take up feed roll 15 and when the towel web is wound on the take up roll it will contact by gravity with the take up feed roll and be revolved 35 to wind up the soiled towel synchronously with the unwinding of the clean towel. Holes 24 are preferably provided in the plates 7 to receive a hook 25 that is mounted in the side wall of the cabinet and is adapted to support the swinging frame in its withdrawn 40 position or at the time when the attendant is using both hands in threading the towel upwardly to the soiled towel take up roll. I prefer also to provide a stop 27 in the wall 45 of the cabinet to limit the inward swinging movement of the pivoted frame.

The operation of filling the cabinet is as follows: The attendant having opened the door of the cabinet and found the clean towel supply exhausted will reach in over the pivoted frame and withdraw the loaded take up roll out through the guides 22 and remove the take up roll from the soiled towel roll. Then he will place the supply of clean towel 50 in the pivoted frame and stretch the loose end up over the pinch roll. He will then draw the pivoted frame forwardly to a point where the hook 25 will engage the eye or hole 24. At that point a considerable gap 55 or opening will be provided in the rear of the pivoted frame so that the attendant can easily stretch or thread the loose end of the web upwardly through the cabinet and over the pivoted frame to a point where the loose end can be easily and quickly wound on the

take up roll as indicated in Figure 2. This having been done, the pivoted frame will be released and allowed to swing back by gravity within the cabinet and the take up roll will then be inserted in the guides 22 and moved inwardly therein to the position indicated by full lines in Figure 1, a sufficient length of towel web having been wound on the take up roll to insure the revolution of the roll upon contact with the feed roll and also to provide a loop of sufficient length below the towel cabinet. 75

I claim as my invention:

1. A towel cabinet comprising a casing, a frame therein, comparatively long links 80 pivotally connecting said frame with said casing, said links allowing said frame to be drawn forwardly to a position partially outside of said casing, to provide a gap or space in the rear of said casing, a soiled towel take 85 up roll in the rearward upper portion of said casing delivery and take up feed rolls mounted in said frame, the delivery roll being mounted in front of the take up feed roll and having a driving connection between them, 90 said rolls having surfaces adapted to cling or adhere to a towel web, a pinch roll between which and said delivery feed roll the clean towel web may be stretched for driving 95 contact with said delivery feed roll, said frame having outwardly opening slots in which said pinch roll normally rests the loose 100 end of the clean web adapted to be stretched downwardly to form a loop, a gap or opening provided in the rear of said casing by the forward movement of the frame providing a passage through which the hand of the attendant may be inserted when said frame is swung forwardly, said take up roll being removable from said cabinet for convenience 105 in winding the loose end of the web thereon, said cabinet having guides wherein said take up roll is inserted for contact of the towel web thereon with said take up feed roll.

2. A towel cabinet comprising a casing, a frame therein, links pivotally connecting said frame with the walls of said cabinet and permitting said frame to be drawn forwardly to a point partially outside of the cabinet, delivery and take up feed rolls journaled in said frame and having a driving connection between them and provided with surfaces adapted to adhere to a towel web, said frame having a clean towel compartment 115 normally resting on the bottom of the cabinet said compartment having an open front and closed rear whereby a web of clean towel may be stretched upwardly to contact with said delivery feed roll and thence depend to form a loop below the cabinet, a hook device for holding said frame in its forward or projected position, space being formed in the rear of said frame when it is swung forward to allow convenient insertion of the web of towel and the stretching of the web forward. 120 125 130

ly above said frame to a point outside said casing, and a take up roll mounted in guides in the wall of said casing and whereon the loose end of the towel web may be conveniently wound when the roll is withdrawn from its guides, a web of towel on said take up roll being adapted to contact with the surface of said take up feed roll and to be revolved thereby when said take up roll is reinserted 10 into said guides.

3. A towel cabinet comprising an outer casing having guide slots therein on its sides and also having a bottom shelf, a take up roll with its pivots movable in said slots, an 15 inner casing open at its front but closed at its rear normally resting on said bottom shelf and carrying feed rolls on one of which normally rests said take up roll, links pivoted to both casings and the inner casing being 20 swingable on said links from its position on said shelf to a position at least partially outside the outer casing to cause an opening back of the inner casing through which a towel web looped below the casing may be 25 threaded to the take up roll.

In witness whereof, I have hereunto set my hand this twenty-second day of January, 1927.

GEORGE ADOLPH STEINER.
